THOMAS DOLAN, OF PHILADELPHIA, PENNSYLVANIA.

Design No. 3,132, dated July 28, 1868.

DESIGN FOR A KNITTED FABRIC.

The Schedule referred to in these Letters Patent and making part of the same.

TO ALL WHOM IT MAY CONCERN:

Be it known that I, THOMAS DOLAN, of the city and county of Philadelphia, State of Pennsylvania, have invented or produced a new and original Design for a Knitted Fabric; and I do hereby declare that the accompanying drawing, and the following explanation thereof, form a full, clear, and exact description of the said design.

The drawing represents the design so clearly, that a minute description will be unnecessary. It may be remarked, however, that the body of the fabric consists of plain knitted loops, united to and forming combinations of the scalloped edging, the configuration of which is clearly indicated in the drawing.

I claim the design for a knitted fabric, substantially as represented in and by the accompanying drawing. In testimony whereof, I have signed my name to this specification in the presence of two subscribing witnesses.
